UNITED STATES PATENT OFFICE.

MARTIN LOUIS, OF KIEL, GERMANY, ASSIGNOR TO FRIED. KRUPP GERMANIAWERFT AKTIENGESELLSCHAFT OF KIEL-GAARDEN, GERMANY.

DIESEL ENGINE.

Application filed March 9, 1927, Serial No. 174,042, and in Germany April 24, 1926.

- In Diesel engines which operate with pre-compressed charging air to increase their efficiency, in the normal operation (without pre-compression) the pressure of the compression is chosen to be as low as possible—as far as this is still possible with respect to a secured ignition—in order to not have a too high end pressure of the compression, when the initial pressure is increased by said pre-compression. To maintain further the maximum pressure of the combustion within admissible limits, when pre-compressed air is used, a combustion under constant pressure has to be aimed at if possible, whilst for the normal service (without pre-compression) and for a low end pressure of the compression a combustion under a somewhat increased pressure is to be aimed at, to obtain a good thermodynamic efficiency of the machine. As it is known, the course of the pressure arising during combustion may be influenced by suitably adjusting the pre-injection of the fuel. Now my invention has for its object to afford a means for automatically regulating, in machines in which the moment of injection is determined by the fuel pump, the extent of the precompression in correspondence to the pre-injection of the fuel. This object is obtained according to my invention by automatically adjusting the rigging serving to determine the moment of the pre-injection, by means of a controlling piston which is under the action of the pre-compressed air.
- In order that my invention may be more easily understood, a preferred embodiment of same is diagrammatically illustrated in the drawing which accompanies and forms part of this specification.
- Referring to this drawing, A denotes the fuel pump of the Diesel engine the piston B of which pump is actuated by a cam disk D through the intermediary of a rod C. The latter carries rollers on both its ends and is linked on one end by a rod E to a fixed point F, whilst its other end may be swung about a shiftable point H by intermediary of a link G. Point H is formed by one end of an angle lever J adapted to swing about a fixed point K and the other end of which is connected to a piston M by a link L. Piston M may reciprocate in a cylinder N. The space above piston M is connected by a pipe O to the pressure piping (not shown) of the pump sup-
- plying the pre-compressed charging air. Below the piston M is arranged in the cylinder N a spring P. A hand wheel Q is further provided the shaft R of which serves as an adjustable abutment for piston M.
- The described device operates as follows:
- When the pressure of the charging air is increased by pre-compression, the pressure prevailing in the piping connecting the blower and the machine is transmitted through pipe O to piston M, which is then lowered against the action of spring P until the force of the latter and the air pressure above the piston are in equilibrium. The downward motion of piston M causes the point H to swing to the right, as shown by dot and dash lines, through the intermediary of link L and bell crank lever J. Point H carries along with it to the right the upper roller of link C, by means of link G. With the cam disk D rotating in the direction indicated by the arrow, this right-hand motion causes the upper roller of link C to ascend on the cam of disk D later. Consequently, the motion of the piston B of the fuel pump A, and therefore the supply of fuel and the injection period commence later.
- Of course, my invention is not limited to machines with which the entire combustion air is pre-compressed; it may on the contrary, be employed also with machines with which only that portion of the combustion air is pre-compressed that serves for the supplemental charge.
- What I claim and desire to secure by Letters-Patent, is:
- In a Diesel engine operated with pre-compressed charging air and pre-injection of the fuel, a fuel pump, a rod adapted to actuate said pump, a cam disk actuating said rod, a cylinder, a piston adapted to reciprocate therein and being under the pressure of the pre-compressed charging air, a yielding means adapted to act on said piston against the action of said air pressure, a rigging connected to said rod and to said piston and adapted to adjust said rod with relation to said cam disk in accordance with the motions of said piston.
- The foregoing specification signed at Hamburg, Germany, this tenth day of February, 1927.

MARTIN LOUIS.
